UNITED STATES PATENT OFFICE.

JAMES FRANKLIN HIGGINS, OF NEW ORLEANS, LOUISIANA, ASSIGNOR TO HYDRO-CARBON GAS GENERATOR COMPANY, INCORPORATED, OF NEW ORLEANS, LOUISIANA, A CORPORATION OF LOUISIANA.

FLUID-FUEL APPARATUS.

1,246,004.

Specification of Letters Patent.

Patented Nov. 6, 1917.

Application filed October 7, 1916. Serial No. 124,315.

To all whom it may concern:

Be it known that I, JAMES F. HIGGINS, a citizen of the United States, residing at New Orleans, in the county of Orleans and State 5 of Louisiana, have invented certain new and useful Improvements in Fluid-Fuel Apparatus, of which the following is a specification, reference being had therein to the accompanying drawing.

10 This invention relates to an apparatus for converting into gas various grades of oils and burning it in an efficient and economical manner, and the arrangement is such that steam and oil are passed separately through 15 a superheater in a furnace or the like with which the apparatus is associated and superheated therein without carbonization of the oil and then conveyed to a carbureter and burner wherein they are mixed as gases and 20 whence the mixture is discharged into a fire-box.

It is an object of the invention to provide an apparatus of this kind that is adapted to consume in a satisfactory manner without 25 carburization in the superheater and the pipes that lead therefrom heavy oils in their natural state and the heavier bases thereof remaining after the lighter products are removed in a refining process.

30 When read in connection with the description herein, the details of construction and arrangement of parts contemplated by the invention will be apparent from the accompanying drawings, forming part hereof, 35 wherein an embodiment of the invention, as adapted to a boiler-furnace, is disclosed, for purposes of illustration.

While the disclosures herein now are considered to exemplify a preferable embodiment of the invention, it is to be understood that it is not the intention to be limited necessarily thereto in interpretation of the claims, as various modifications and alterations within the limits of the claims can 45 be made without departing from the nature and spirit of the invention.

Like reference-characters refer to corresponding parts in the views of the drawings, of which—

50 Figure 1 is a fragmentary view of a boiler-furnace, partly in section, showing an installation of the apparatus;

Fig. 2 is a vertical longitudinal sectional view;

Fig. 3 is an end view;

Fig. 4 is a sectional view on the line 4—4, Fig. 2; and

Fig. 5 is an end view of the superheater.

The apparatus as exemplified herein includes a superheater and a mixing carbureter and burner, which are supplied with fluids through a steam-pipe A, leading from a suitable source of supply and having a control-valve A', and an oil-pipe B, leading from a suitable source of supply and having a control-valve B'. A by-pass C leads from the steam-pipe at a place between the source of supply and the control-valve A' to the oil-pipe at a place between the control-valve B' and the superheater, and the by-pass has a control-valve C' between the steam and oil pipes. The apparatus is shown as associated with a boiler-furnace, of which the boiler is designated by D, the fire-box by E, and the front wall thereof by F.

75 The superheater includes an elongated casing 6, preferably tubular, which is set into the front wall F and extends along the bottom of the fire-box almost to its rear end, the casing for the major portion of its length being covered by tiles or the like G. The casing is closed at its inner end, and its outer end opens into an enlarged steam-chamber 7 outside of the fire-box. The chamber is formed by a member 8 screwed onto the end of the casing and having an annular threaded flange 9 onto which is screwed an annular housing 10 closed by an end wall 11, these parts not only forming the steam-chamber, but also closing the superheater-casing at its outer end.

90 The wall 11 has an opening in which is secured and from which projects outwardly a stuffing-box 12. The stuffing-box carries and forms a fluid-tight joint with an elongated outer fuel-tube 13, which may be moved inwardly and outwardly by loosening parts of the stuffing-box. The fuel-tube extends through the steam-chamber 7 and into the superheater-casing nearly to the inner end thereof, and its inner end is closed. A headed collar 14 is threaded onto and closes the outer end of the fuel-tube, and in its end it has an opening into which is secured and from which projects outwardly a stuffing-box 15. The stuffing-box carries and forms a fluid-tight joint with an elongated inner fuel-tube 16, which may be

2

moved inwardly and outwardly by loosening parts of the stuffing-box. The inner fuel-tube is smaller than and extends into the outer fuel-tube nearly to its inner end. 5 The inner end of the inner fuel-tube is open, and the inner fuel-tube is connected at its outer end with the oil-supply pipe B. A pipe 17 having a control-valve 18, leads from the collar 14. 10 The wall 11 also has another opening in which is secured and from which projects outwardly a stuffing-box 19. This stuffing-box carries and forms a fluid-tight joint with a steam-tube 20, which may be moved inwardly and outwardly by loosening parts of the stuffing-box, and which extends through the steam-chamber and into the superheater-casing nearly to its inner end. The steam-tube is open at its inner end, and it is 15 connected at its outer end with the steam-supply pipe A. A pipe 21, having a control-valve 22, leads from an exit 23 of the steam-chamber. The steam-chamber is fitted in its lower portion with a drain-valve 24. 20 When the apparatus is in use, steam under pressure is discharged from the steam-tube into the superheater-casing at its inner end, and oil under pressure is discharged from the inner oil-tube at its inner end. The steam 25 fills the superheater and the steam-chamber surrounding the outer oil-tube, and under the influence of the heat of the fire-box to which the superheater-casing is subjected the steam therein is heated to a temperature of from 1,000 to 1,200 degrees F. The fluid in the superheater surrounding the oil-tubes in turn heats them, and the fuel contained therein is heated during its travel inwardly through the inner fuel-tube and outwardly 30 through the outer fuel-tube. Under usual conditions of operation the fuel in the outer tube is brought to a temperature of from 300 to 500 degrees F. by the time it passes from the area in which it is subjected to 35 heat. As a superheater in a furnace of usual size extends into the fire-box a distance of about twelve feet, the fuel travels a distance of approximately twenty feet in passing through the inner and outer fuel-tubes in the 40 furnace, besides being subjected to heat in the steam-chamber, and this is sufficient to bring the fuel to the required temperature to cause gasification upon liberation. The 45 fuel and steam are discharged from the superheater, respectively, into the pipes 17 and 21. The fuel in the oil-supply pipe is maintained by any suitable means at a constant pressure of from 50 to 100 pounds, the 50 pressure being determined by the particular grade of oil fuel in use, and the temperature to which the fuel in the superheater is subjected is controlled by varying the pressure, and therefor the volume, of the steam that transmits heat to the fuel-tubes, the 55 temperature being raised and lowered by in-

creasing and decreasing the volume. During passage of the fuel under pressure through the superheater, the fuel does not become carbonized, and there is no liability of the fuel becoming clogged on this account. 70

On discontinuing the use of the apparatus by closing the supply-pipe valves A' and B', the by-pass valve C' is opened while the apparatus yet is hot and steam is blown through the tubes and pipes to free them of oil and thereby to prevent carbonization 75 therein.

Each of the pipes 17 and 21 is fitted with a thermometer-tube 25, the pipes lead to and are coupled into a plate 26 set into the front wall 11 and forming the front wall of a burner, and they discharge into a mixing-chamber 27 contained within a casing 28 threaded at its receiving end into the plate. The other end of the casing 28 is contracted 80 and integrally joined with the walls of an outwardly-extending discharge-nozzle 29.

Up to the time of their discharge into the mixing-chamber, the fluids from the oil and steam supply are heated and conveyed separately. Upon liberation into the mixing-chamber, the superheated fluid from the oil tubes immediately becomes gasified and thoroughly mixed with vapor derived from the steam in the superheater and the carbon 90 thereof is assimilated.

The mixture is discharged through the nozzle and is mixed with air drawn thereby from an air-conduit 30 extending through the mixing-chamber and having its discharge-end portion extending into the nozzle. The air-conduit at its other end is threaded centrally into and extends outwardly of plate 26. An air-regulator casing 31, larger than the conduit, is threaded at 105 one end onto the outwardly-projecting portion of the conduit, and its other end portion is exteriorly screw threaded and carries an interiorly screw-threaded regulator cap 32 having side ports 33. The open area of the 110 ports, and thereby the amount of air drawn into the conduit, is regulated by turning the cap in one direction or the other, and the proportion of fuel-gas and steam-vapor admitted to the mixing-chamber is regulated 115 by the valves 18 and 22, all in accordance with the grade of liquid fuel in use and the heat required in the furnace.

Having thus described my invention, what I claim as new, and desire to secure by Letters Patent, is—

1. A superheater for fluid fuel comprising an elongated casing closed at one end, a housing closing a steam-chamber having an exit connected to the other end of said 125 casing and having an end wall, an outer closed fuel-tube extending through said wall into said casing nearly to its other end and having an exit outside of the superheater, an inner fuel-tube adapted to be connected 130

with a source of supply and extending into said outer fuel-tube and arranged to discharge thereinto near its inner end, and a steam-tube extending through said wall 5 into said casing and arranged to discharge thereinto near its other end.

2. A superheater for fluid fuel comprising an elongated casing closed at one end, a member screwed onto the other end of said 10 casing and having an annular threaded flange, an annular housing screwed onto said flange and having an end wall provided with an exit, an outer closed fuel-tube extending through said wall into said casing 15 nearly to its other end and having an exit outside of the superheater, an inner fuel-tube adapted to be connected with a source of supply and extending into said outer fuel-tube and arranged to discharge there- 20 into near its inner end, and a steam-tube extending through said wall into said casing and arranged to discharge thereinto near its other end.

3. In a furnace including a wall and a 25 fire-box adjacent thereto, the combination of an elongated superheater-casing extending through said wall along the bottom of said fire-box, a housing inclosing a steam-chamber having an exit connected to the outer 30 end of said casing and having an end wall, an outer closed fuel-tube extending through said chamber-wall into said casing nearly 35 to its other end and having an exit outside of said chamber, an inner fuel-tube connected with a source of liquid-fuel supply extending into said outer fuel-tube and arranged to discharge thereinto near its inner end, a steam-tube connected with a source 40 of supply extending through said chamber-wall into said casing and arranged to discharge thereinto near its other end, a burner in said furnace-wall above said casing having a mixing-chamber and a nozzle discharging therefrom into said fire-box, a pipe

leading from said steam-chamber exit to 45 said mixing-chamber, and a pipe leading from said outer fuel-tube exit to said mixing-chamber.

4. A superheater for fluid fuel comprising an elongated casing closed at one end, 50 a member screwed onto the other end of said casing and having an annular threaded flange, a cylindrical housing screwed onto said flange and inclosing an enlarged steam-chamber, said housing having an end wall 55 provided with an exit and an opening separate therefrom, a stuffing-box in said opening, an outer closed fuel-tube extending through said stuffing-box nearly to the other end of said casing and having an exit and an 60 axially-disposed opening outside of said end wall, an inner fuel-tube adapted to be connected to a source of supply and extending into said outer fuel-tube nearly to its other end and adapted there to discharge there- 65 into, and a steam-tube extending through said end wall into said casing and arranged to discharge thereinto near its other end.

5. A superheater for fluid fuel comprising a casing having an exit, a steam-discharge 70 pipe leading from said exit, an outer fuel-tube closed within said casing and having an exit outside thereof, a fuel-discharge pipe leading from said fuel-tube exit, an inner fuel-tube extending into said outer fuel- 75 tube and arranged to discharge thereinto, a steam-tube extending and arranged to discharge into said casing, a steam-supply pipe connected to said steam-tube, a fuel-supply pipe connected to said inner fuel-tube, and 80 a valve-controlled by-pass connecting said supply-pipes.

In testimony whereof I affix my signature in presence of two witnesses.
